E. C. HEALY,
SUPERVISORY MECHANISM,
APPLICATION FILED APR. 23, 1918.

Patented Feb. 28, 1922.

Ellis C. Healy Inventor

By his Attorney
Kerr Page Cooper Hayward

UNITED STATES PATENT OFFICE.

ELLIS C. HEALY, OF EAST ORANGE, NEW JERSEY, ASSIGNOR TO NEWMAN CLOCK COMPANY, INC., OF NEW YORK, N. Y., A CORPORATION OF NEW YORK.

SUPERVISORY MECHANISM.

1,407,809.

Specification of Letters Patent. Patented Feb. 28, 1922.

Application filed April 23, 1918. Serial No. 230,247.

To all whom it may concern:

Be it known that I, ELLIS C. HEALY, a citizen of the United States, residing at East Orange, in the county of Essex and State of New Jersey, have invented certain new and useful Improvements in Supervisory Mechanism, of which the following is a full, clear, and exact description.

Valves for controlling the flow of fluids are in such common use that they form a component part of practically every mechanical equipment in general use. Under certain conditions it is essential that they should remain open or remain closed at all times except for making repairs, extensions or for other recognized purposes; and it is a well recognized fact that loss of life and great damage has resulted through oversight or design in permitting valves to remain closed when their normal position should be open, and vice versa.

The invention which constitutes the subject matter of this application relates to supervisory mechanism, specifically described in connection with sprinkler systems. The use of automatic sprinkler systems is coming more and more into vogue, but like all other systems of water distribution the valves at times must necessarily be closed temporarily in order to effect repairs, to prevent freezing, and for many other purposes. There has been and is a tendency on the part of workmen to leave one or more of the valves closed, thereby putting a part or the whole of the system completely out of commission with a result of considerable losses in cases of fire.

My invention therefore has to do with a fluid pressure mechanism adapted to be connected to a valve for controlling the access to a recording key located adjacent thereto. That is to say when the valve is open, as it normally should be, access may be had to the key, but if the valve is closed the key is not available. As each one of these valves (or "stations") is equipped with a key a time-print may be made on a record dial of a watchman's clock which would indicate the time at which the station was visited. So long as these imprints are made at the required intervals, as shown by the record dial, it is a sure indication that the valves at those particular times were opened. But if the imprint of a certain station were omitted from the record dial it would be an equally

sure indication that the key at that station was inaccessible and therefore the valve was closed. Of course if it is a part of the watchman's duty to open the valve he could then make the imprint. In any event the device will have served its purpose.

Another feature of my invention consists in providing a device of the kind described by which the key box may be located at any desired distance from the corresponding valve. For example, all the key boxes controlled by the various valves may be located at the same point, thereby facilitating the making of the records.

Referring to the drawing in detail, Figs. 1 and 2 illustrate a side view of the preferred embodiment of my invention, parts being in section to show the interior construction, and Fig. 3 is a section taken at right angles to Fig. 2. The reference numeral 10 designates the water supply to the sprinkler coming from any suitable pipe (not shown). Located in this supply is a valve 11 provided with a yoke 12, a threaded sleeve 13 rotatably mounted in the yoke, a valve stem 14 screw-threaded to the sleeve, and a manipulating handle 15 fixed to the sleeve 13 and adapted to rotate the same in order to impart a longitudinal movement to the valve-stem 14 and the gate valve (not shown) attached thereto.

The mechanism just described is old and well known and I make no claim thereto, except as it constitutes or is an element of the combination.

Located in proximity to the valve just described is the controlling mechanism which comprises a pipe or tubular member 16, screwthreaded or otherwise connected to the supply 10 on the one hand and to the case 17 on the other, and this pipe, in conjunction with the passages 18 and 19 in said casing, establishes a connection between said supply 10 and the chamber 20. Separating the passages 18 and 19 is a valve 21 held normally closed by means of the spring 22 encircling the stem 23, and within the chamber 20 is a plunger 24 normally held in the position illustrated by means of the spring 25 surrounding the stem 26 upon the outer end of which is a rack 27 screwthreaded or otherwise attached thereto. Connecting the passage 19 with the exterior are one or more bleed ports 28 adapted to be closed by means of a valve 29, provided with a stem 110

30 and spring 31. Pivoted at 32 to a bracket 33 is a lever one arm 34 of which is adapted to engage the outer end of the stem 23 and the other arm 35 of which is 5 adapted to engage the outer end of the stem 30.

Also pivoted at 36 to the bracket 33 is a bell crank lever one arm 37 of which is 10 adapted to bear against arm 34 of lever 34—35 and the other arm 38 of which is provided with an antifriction roller 40 normally engaging in a recess 41 cut in the valve stem 14. It will, therefore, be obvious that if the stem 14 is moved in a direction 15 to close the valve attached thereto a counter-clock wise movement will be imparted to the lever 37—38. This will also result in imparting a counter-clock wise movement to the arm 34—35 thereby 20 positively opening the valve 21 and permitting the valve 29 to close. This operation establishes a connection between the pipe 10 and chamber 20 with a result that the plunger 24 is depressed, that is moved to 25 the left against the tension of the spring 25.

It may be stated at this point that when the valve stem 14 is moved back to normal position the valve 21 will be closed and the valve 29 opened under the tension of the 30 spring 22, and that when the valve 29 is opened the tension of the spring 25 is sufficient, among other things, to force the water out of the chamber 20 to return the plunger 24, stem 26 and rack 27 to normal 35 position.

At 42 is illustrated a receptacle provided with two compartments 43 and 44. In compartment 43 there is provided a shaft 45 rotatably journaled therein and actuated by 40 the rack 27 by means of the pinion 46, in mesh with said rack, and the flexible shaft 47 one end of said flexible shaft being connected to said pinion and the other end of which is connected to the shaft 45. Fixed 45 to the shaft 45 is a gear 48 which meshes with a pinion 49 located on the shaft 50 of the key-drum 51. Attached to the periphery of the drum 51 is a key chain 52 to which is secured a key 53. The key chain 50 extends downwardly through the perforation 54 in the partition 55 into the key compartment 44.

The key compartment is provided with a door 56 provided with a catch 57. Located also upon the shaft 45 is a drum 58 provided with a cam slot 59 adapted to actuate the lock 60, in the partition 55, to engage the catch 57.

In the normal position of the parts as 60 illustrated the chain is unwound and the watchman in making his rounds has access to the key in compartment 44. If the valve 11 is now moved towards its closed position the fluid pressure mechanism is set into operation, the key chain wound up around the

drum and the key moved to the position illustrated in dotted lines in Figure 2 and in full lines in Figure 3, and in this position there is not enough slack in the chain to enable the watchman to make a record on the record dial. The door should be closed at all times except when the watchman is making his visit, and if closed, as it should be, it will be locked simultaneously with the winding up of the chain. 75

From the foregoing it will be seen that I have provided a simple mechanism actuated by the pressure in the pipe 10 to prevent the watchman from making a record while visiting that particular station, providing the valve is not in proper position. In operation the supervisor visits each valve equipped with my invention and if the valve is found to be closed or open as the particular system requires, it is then 80 possible for him to obtain the key in order to make a registration upon his watchman's clock, which is indisputable evidence that the valve was at that time and place in normal position. If, however, the supervisor should be unable to obtain the key he would then know that the valve is not in its normal position, and he would thus be unable to effect the registration until the valve had been restored to normal position. And if the 85 dial on the watchman's clock does not show a registration covering all the valves which he is required to supervise it could be readily determined which valve or valves he had found not to be in normal position. 90

In certain of the claims I employ the expression "translating device." By "translating device" I mean a device or instrument whereby one form of energy is converted into another. In the present application a translating device for converting fluid pressure to mechanical motion, is disclosed. In short, I employ the expression in the sense within the following definition found in Knight's Mechanical Dictionary: Translator—An 100 instrument whereby one form of energy is converted into another. 105

As before stated, the construction illustrated and described is merely one of the preferred embodiments and it is to be understood that I do not limit myself thereto as it is obvious not only that many changes may be made in point of detail but that other embodiments may be resorted to without departing from the true spirit and scope of my invention as defined in the following claims. 115

What I claim is:

1. A supervisory mechanism for a sprinkler system comprising a supply, a valve in said supply, and a container for a watchman's 125 key, in combination with a fluid pressure means set by the actuation of said valve for controlling the access to said key.

2. A supervisory mechanism for a sprinkler system comprising a supply for the 130

5 sprinkler, a valve adapted to shut off said supply, securing means for a watchman's key, in combination with a fluid pressure mechanism set by the actuation of said valve, and means operated by said pressure mechanism to render said key inaccessible for making a record.

10 3. The combination with a normally open valve, of a container for a watchman's key, said key being normally accessible, means in said container for rendering said key inaccessible, and fluid pressure means adapted to actuate the aforesaid means when the valve is moved towards its closed position.

15 4. The combination with a normally open valve, of a recording means normally operative for making a record, means for rendering said recording means inoperative, and fluid pressure means adapted to actuate the aforesaid means when the valve is moved 20 towards its closed position.

25 5. The combination with a normally open valve, of a recording means normally operative for making a record, means for rendering said recording means inoperative, and a fluid pressure means adapted to actuate the aforesaid means when the valve is moved 30 towards its closed position but adapted to return said recording means to operative position when the valve is brought back to normal.

35 6. In combination, a normally open valve, a translating device controlled thereby, a manually operable indication-producing means, and means controlled by said translating device for preventing manual operation of said first mentioned means when said valve is in abnormal position.

7 In combination, a valve, a recording device, a translating device controlled by said valve, and means including said translating device for preventing operation of said recording device unless said valve is in a predetermined condition.

8. In combination, a valve, a translating device controlled thereby, a watchman's key, and means including said translating device for preventing access to said key unless said valve is in a predetermined condition.

9. A supervisory mechanism for a sprinkler system comprising a fluid supply pipe, a manually operable indication-producing means, a pressure-responsive device connected to said pipe, and means comprising said device for preventing manual operation of said first named means when said system is in an abnormal condition.

10. A supervisory mechanism for a sprinkler system comprising a fluid supply pipe, a supply-control valve therein, a manually operable indication-producing means, a pressure responsive device connected to said pipe and controlled by said valve, and means comprising said device for preventing manual operation of said first named means when said valve is in an abnormal position.

11. A supervisory mechanism as set forth in claim 9 in which the indication-producing means is a watchman's key.

12. A supervisory mechanism as set forth in claim 10 in which the indication-producing means is a watchman's key.

In testimony whereof I hereunto affix my signature.

ELLIS C. HEALY.
